(57) **CLAIM**

The ornamental design for an internal snap member, as
shown.

DESCRIPTION

FIG. 1 is a front, top and right-side perspective view of an
internal snap member showing a first embodiment of our new
design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is a front, top and right-side perspective view of an
internal snap member showing a second embodiment of our
new design;

FIG. 9 is a front view thereof;

FIG. 10 is a rear view thereof;

FIG. 11 is a top plan view thereof;

FIG. 12 is a bottom plan view thereof;

FIG. 13 is a left side view thereof; and,

FIG. 14 is a right side view thereof.

1 Claim, 14 Drawing Sheets
